CLAIM

The ornamental design for a folding makeup tool as shown and described.

DESCRIPTION

FIG. 1 is a perspective view of a folding makeup tool showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of a portion of the folding makeup tool shown within the area designated as 9 in FIG. 2.

The evenly spaced dashed broken lines and the dot-dot-dash broken lines depict portions of the folding makeup tool that form no part of the claimed design. The dot-dash broken lines encircling portions of the folding makeup tool in FIG. 2 and illustrated in the enlarged view in FIG. 9 form no part of the claimed design.

1 Claim, 9 Drawing Sheets
